CLAIM

The ornamental design for a container for freezing and storing food products, as shown and described.

DESCRIPTION

FIG. 1 is a top perspective view of a container for freezing and storing food products showing my new design;
FIG. 2 is a right side elevational view thereof;
FIG. 3 is a left end elevational view thereof;
FIG. 4 is a right end elevational view thereof;
FIG. 5 is a top plan view thereof;
FIG. 6 is a left side elevational view thereof;
FIG. 7 is a bottom plan view thereof; and
FIG. 8 is a top perspective view thereof showing a modification of my new design.

FIG. 2

FIG. 3

FIG. 4

FIG. 6

FIG. 7

FIG. 8
